UNITED STATES PATENT OFFICE

161,581

COMBINED SPINNER AND TOP

Al Greene, New York, N. Y., assignor to Lapin Products, Inc., Newark, N. J., a corporation of New York

Application December 31, 1948, Serial No. 150,495

Term of patent 14 years

(Cl. D34—15)

To all whom it may concern:

Be it known that I, Al Greene, a citizen of the United States and a resident of the city, county, and State of New York, have invented a new, original, and ornamental Design for a Combined Spinner and Top, of which the following is a specification, reference being had to the accompanying drawings, forming part hereof and in which:

Fig. 1 is a side elevational view of a combined spinner and top showing my new design.

Fig. 2 is a bottom plan view of the combined spinner and top.

Fig. 3 is a front end elevational view of the combined spinner and top, and

Fig. 4 is a side elevational view of the combined spinner and top on the opposite side from the showing of Fig. 1.

I claim:

The ornamental design for a combined spinner and top, substantially as shown.

AL GREENE.
